UNITED STATES PATENT OFFICE.

WILLIAM H. CHACE, OF FALL RIVER, MASSACHUSETTS.

MACHINE FOR STRETCHING LEATHER BELTING.

SPECIFICATION forming part of Letters Patent No. 232,454, dated September 21, 1880.

Application filed May 25, 1880. (No model.)

To all whom it may concern:

Be it known that I, WILLIAM H. CHACE, of Fall River, State of Massachusetts, have invented a Machine for Stretching Leather Belting, of which the following is a specification.

Figure 1 of my invention is a representation of a side view, and Fig. 2 is a top view of the same.

This invention has relation to machines for stretching leather belting and retaining the same in a stretched condition a sufficient length of time to prevent the leather belting so stretched from losing the degree of tension to which it is stretched.

It consists in the novel arrangement of a delivering-drum, a removable receiving-drum, guide-flanges on each side of the latter, cone-pulleys and connecting-belt for varying the speed of the receiving-drum, the belt-shifter, and removing-screw for the receiving-drum, all as hereinafter shown and described.

In the accompanying drawings, the letter C designates the drum on which the belting to be stretched is wound, and from which it is delivered to the receiving-drum B, which is arranged at a suitable distance from the delivering-drum on the frame A, running between the guiding-flanges F F', one of which is adjustable by means of a screw, H, passing through a threaded box, E, on the frame, and serving as the journal for the said flange F'. By means of these flanges the belting a is kept straight as it is rolled on the receiving-drum.

Between the delivering and receiving drums are journaled, on the frame, the cone-pulleys A' A'', which are connected by a shifting-belt, b, the position of which on the pulleys, which taper in opposite directions, is governed by the arms c of a shifter, d, which is moved by a

transverse screw, G, journaled to the frame of 40 the machine.

D represents a friction-pulley attached to the fixed flange of the delivering-drum and engaging with a brake or friction-arm, e, and serving to keep a uniform stretch on the belt- 45 45 while being wound, preventing the delivering-drum from slipping and running too fast under the strain of the belting being stretched.

Suitable pulleys and gearing are provided for the connection of these drums, as follows: 50 Power is applied at p to the shaft of the delivering-drum. This shaft is geared to the short shaft of the pulley r, which is connected to the pulley s of the first cone. This is connected to the second cone by the shifting-belt 55 b, and the second cone is geared to the shaft h of the receiving-drum, so as to run at a speed faster than that of the delivering-drum, this rate of speed being regulated by the governing-cones A' A''. This cone-connection also 60 serves to prevent the belt from breaking under undue strain because it is not rigid, but is effected by means of a friction-belt, b.

Having described my invention, what I claim, and desire to secure by Letters Patent, 65 is—

In a machine for stretching leather belting, the combination of the delivering-drum C and the removable receiving-drum B, having the flanges F F', the latter being adjustable by 70 means of screw H, with the cone-pulleys A' A'', having the belt b to regulate the motion of said receiving-drum, and the transverse screw G for operating the shifter d, substantially as specified.
